UNITED STATES PATENT OFFICE.

STANLEY L. APOLANT, OF JERSEY CITY, NEW JERSEY.

METHOD OF PERFORMING SKIN-GRAFTING OPERATIONS AND SURGICAL INSTRUMENT
USED THEREFOR.

Application filed November 2, 1921. Serial No. 512,183.

To all whom it may concern:

Be it known that I, STANLEY L. APOLANT, a citizen of the United States, and resident of Jersey City, New Jersey, have invented 5 certain new and useful Improvements in the Method of Performing Skin-Grafting Operations and Surgical Instruments Used Therefor, as set forth in the following specification.

10 This invention relates to an improved method of performing skin grafting operations and to a surgical instrument thought to be the first of its kind ever designed for stripping the epidermis from a portion of 15 the body, of either a person or an animal, so that it can be used in a skin grafting operation.

Heretofore surgeons in performing grafting operations have been obliged to depend 20 almost wholly upon their skill or that of an assistant to hold the epidermis while they stripped the same by use of a hand-operated blade having a keen edge, an ordinary razor having often been used. This procedure at 25 best is somewhat a crude one and often requires the service of two or more persons to skillfully and properly remove the desired amount of skin to be used for the graft. A difficulty usually encountered when performing 30 grafting operations is that the epidermis has a tendency to curl which interferes with its handling and its proper placing on the wound of the patient.

Utilization of my improved method overcomes the above objections and my novel instrument provides means whereby operations of this nature can be performed more skillfully and quickly and in such manner that the thickness of epidermis removed can be 40 very accurately predetermined. It also provides means for holding the epidermis taut both before and after it is removed from the body.

Among the principal objects of the invention are:—the improvement of the method of performing skin grafting operations. The provision of means for mechanically driving a knife to remove the epidermis, and means for holding the skin taut, during 45 the stripping operation; to provide a frame holder adapted to be removed from the instrument together with the portion of skin stripped; the provision of a flexible frame having angularly deposited needle points to

hold the epidermis in place, said frame being adapted to be flexed or warped to fit the contour of the portion of the body of the patient on whom the graft is made; the provision of a frame holder having a transparent bottom to permit the surgeon to have a clear view of the knife blade while the epidermis is being stripped. The provision of means for adjusting the plane in which the knife blade operates to determine the thickness of the epidermis removed. The provision of a supporting frame for the instrument which is open at the top and bottom to permit a view of the movement of the knife. The provision of means for reciprocating the knife blade transversely and synchronously feeding it longitudinally. The provision of means for automatically discontinuing the feeding movement of the knife after it has completed the stripping operation. The provision of a guard adapted to permit the knife to move vertically without cutting into the epidermis while the instrument is in place and also adapted to bulge or hold the portion of epidermis to be removed in position to be subsequently stripped by the knife blade. The provision of needle frames having points of varying lengths to correspond to the different thicknesses of epidermis to be removed and the provision of a gage calibrated to correspond with the length of the needles carried by said frames to assist in setting the blade to move in the proper plane. The provision of a frame having needles of polygonal cross-section. The provision of vertically adjustable means for guiding the knife blade. The provision of knife guiding means arranged so that they can be readily removed from the frame of the machine to permit cleansing. The provision of means whereby the knife blade can be sprung into and out of position to permit its cleansing. The provision of detachable guides and guards adapted to be removed for cleansing purposes. The provision of parts made of non-corrosive metal to improve the anti-septic character of the instrument. Another object is to combine and organize the various elements herein described so that they effectively perform their functions as set forth. Other objects will be apparent from the following description when read in connection with the accompanying drawings

which illustrate a novel form of surgical instrument by which the improved skin grafting method can be practiced.

Fig. 1 is a longitudinal vertical section 5 illustrating an instrument embodying novel features;

Fig. 2 is a transverse section of the instrument on the plane of line 2—2 of Fig. 1;

Fig. 3 is an end elevation of the instrument viewed from the right hand end of Fig. 1;

Fig. 4 is a side elevation viewed from the right hand side of Fig. 2;

Fig. 5 is a detail view of a clip for rotat- 15 ing a guide;

Fig. 6 is an enlarged section through a portion of the flexible needle frame;

Figs. 7 and 8 are respectively plan and 20 side views of a staple from which the needle points are formed;

Fig. 9 is an isometric view of a detachable transparent needle frame holder showing the needle frame in place;

Figs. 10 and 11 are top views showing re- 25 spectively the pilot nut guide and the head piece guide.

Figs. 12, 13, 14, 15 and 16 are isometric views illustrating respectively the head piece, the pilot carriage, the guide yoke and 30 details of the cross arm which support the knife blade in such manner that it can be reciprocated transversely in one direction and fed horizontally.

Fig. 17 is a view of the needle frame de- 35 tached from the frame holder and holding the piece of stripped epidermis;

Fig. 18 is an isometric view of the main supporting frame of the instrument with 40 all parts removed except the detachable guard;

Fig. 19 is a detail of a gage used to determine the thickness of epidermis on the given portion of the body.

Referring to the drawings the frame 20 45 is of rectangular formation having side walls 22 and 24 and end walls 26 and 28, the wall 26 being higher than the wall 28 to form an extended lip 30 for a purpose to be hereinafter referred to. The walls 22 50 and 24 are provided with sockets 32 and 34, 36 and 38 to receive the ends of a guard 40 formed of side members 42 which are connected by a cross member 44. The guard 40 is so shaped, as best shown in Figs. 1 and 55 18, that the members 42 are located a substantial distance below the sides 22 and 24 of the main frame, and the cross bar 44 of the guard is located a short distance forward of the end wall 28. This arrangement per- 60 mits the frame to be placed against a fleshy portion of the body so that the epidermis will bulge up between the lip 30 and the cross bar 44, as shown in Fig. 1. The longitudinal bars 42 of the guard also bear 65 against the body and these members with the

cross bar 44 and the extended lip 30 confine a substantially rectangular portion of epidermis.

Detachably secured to the underside of the frame 20 is a needle frame holder 70 50 adapted to hold a flexible frame 60 having needles therein which enter the epidermis and hold it taut both before and after it is stripped. The frame holder 50 comprises a bottom plate 52 having side 75 flanges 54 which frictionally engage the outer surfaces of the walls 22 and 24 of the main frame. The plate 52 is provided with offset lips 56 in which is seated a sheet of plate glass or other transparent material 58. At its forward end the plate 50 is bent 80 downwardly and inwardly to form a lip 51 and at the opposite end a pair of ears 53 are struck down from the plate to hold the transparent slab 58 in place. The inner 85 edges of the offset lips 56 are bevelled as shown at 57 to form dovetail ways for a needle frame 60. This frame is rectangular and is open in the center as shown in Fig. 17. It is formed of sheet metal folded on itself as 90 shown in Fig. 6 and between the upper thickness 62 and the lower thickness 64 of the frame is interposed the body portions 66 of staples 68 which have depending pins or 95 needle points 70 formed thereon. The pins 70 at the forward end of the needle frame 60 and at the sides thereof are inclined downwardly and forwardly and the needle points at the rear end of the frame 60 project downwardly and rearwardly. That is to say, the 100 points on three sides of the frame project down at an angle in one direction and those on the fourth or rear end of the frame project in the opposite direction. This disposition of the points is clearly shown in Fig. 1. The 105 needles 70 are preferably of polygonal cross-section as illustrated in Figs. 6 and 7, and they are conveniently formed by swaging them to the shape shown in full lines in Fig. 8 and subsequently bending them as indicated in dotted lines. 110

Needles of polygonal cross-section having points as shown enter the skin more readily than round pointed ones and cause less tearing or stretching of the skin, in 115 other words they enter the flesh with what might be termed a "cutting action." The angular disposition of the needles prevents the epidermis from slipping away from the needle frame both during the cutting operation and after it is stripped from the body. When the needle frame is applied to the body it is, of course, held by the frame holder 50 which is in turn secured to the main frame 20 of the instrument. A forward and downward pressure is first exerted on the frame 20 which forces the forwardly inclined points 70 into the epidermis. Downward pressure is then exerted over the rear portion of the frame 60 which causes 120 125 130

the row of oppositely inclined needles to enter the epidermis, the natural elasticity of the skin then holding it taut between the oppositely inclined needles and flat against the underside of the slab 58.

The skin is now held taut and in position to be stripped by the mechanically driven means to be described. During the cutting movement of the knife blade, the guard 40, 10 needle frame 60 and frame 20 positively hold the portion of epidermis to be stripped in proper position to be removed by a power driven knife.

Reference to Fig. 1 will show that the 15 lower extremities of the needle points 70 are located a substantial distance above the upper surface of the rods 42 of the guard 40, and the knife blade 80 in the starting position shown is located to the rear of the guard 20 44 and in a plane between the rods 42 of the guard and the lower extremities of the needle points.

Means are provided for reciprocating the knife blade 80 transversely and at the same 25 time feeding it longitudinally from the full line position to the dotted line position shown in Fig. 1. The blade 80 is carried by a cross-arm 82 having depending portions 84, the lower ends of which are undercut 30 to form dove-tail tenons 86 which enter mortises 88 formed in the knife blade. The cross-arm 82 is formed of material sufficiently resilient to permit the arms 84 to be sprung into engagement with the mortises 35 88 formed in the knife blade. This arrangement permits of ready removal of the blade for the purpose of cleansing or sterilizing. The cross-arm 82 is provided also with inner depending lugs 83 which are adapted to 40 co-act with an eccentric 90 which is slidably mounted on a feed screw 100. The feed screw is of square cross-section and formed with interrupted threads 102 on the corners. The eccentric 90 is formed with a smooth 45 square opening 92 so that it rotates with the feed screw and at the same time is capable of sliding longitudinally thereon. This eccentric is also provided with flanges 94 which form an annular groove into which 50 the lugs 83 extend, and said flanges bear against the inner surfaces of the walls 112 of a pilot carriage 110. Extending longitudinally from and formed integrally with the walls 112 are hubs which are internally 55 threaded to form pilot nuts 114 adapted to co-act with the feed screw 100, so that as the latter is rotated the pilot carriage will be moved longitudinally. The walls 112 of the pilot carriage are formed at each end 60 with upper grooves 111 and lower grooves 113 which at different times engage pilot guide rods 120 detachably secured to the walls 22 and 24 of the main frame adjacent the inner surfaces thereof. These guide rods are cut away at 122 and 124 near each

end forming interruptions to permit the pilot carriage to be lifted so that the pilot nut can be disengaged from the feed screw 100. To the ends of each of the guide rods, collars 126 are secured by means of suitable 70 screw threads formed thereon. And between the collars and the end walls of the frame are located clips 127 which are slotted at 128 to fit over the rods 120, these clips are carried by head-piece guide-rods 130 secured adjacent the outer surfaces of the walls 22 and 24 of the main frame. The guide rods 130 are cut away or interrupted at 132 and are each provided at one end with a collar 134 secured by means of suitable screw threads, and at the other end with a collar 135 having a slot 136 formed therein into which fits a tongue 137 formed on the end of a thumb piece 138. The end of each guide rod 130 is also slotted to fit the tongue 137 so that as the thumb piece is turned the guide rod 130 will also be turned. This arrangement provides convenient means for detachably securing the guide rods to the main frame and the interrupted portion 132 of the guide rods 130 permits the head piece 140, to be hereinafter referred to, to be removed without necessarily removing the guides. The head piece 140 is formed with walls 142 and 144 which are slotted at 146 and 148 to form guides for projections 116 and 118 extending outwardly from the pilot carriage 110. The walls 142 and 144 of the head piece are offset on their inner surfaces to form shoulders 141 and 143 which are adapted to ride on the upper edges of the side walls 22 and 24 of the main frame. Below the shoulders 141, 143, the extensions are provided with 90 grooves 145 and 147 formed to fit and slide on the head-piece guides 130 carried by the main frame. 95

Located between the walls 112 of the pilot carriage 110 is a guide yoke 150 whose width is slightly less than the distance between the inner surfaces of the walls 112 of said pilot carriage so that the guide yoke can be moved relatively thereto. The guide yoke is formed with a boss 151 which is tapped at 152 to receive the threaded shank of an adjusting screw 160 which screw passes freely through apertures 149 and 119 formed respectively in the head piece 140 and the pilot carriage 110. Located between the pilot carriage 110 and the guide yoke 150 is a leaf spring 171 the ends 173 of which bear against the underside of the pilot carriage and the center portion 174 which is flattened and bears on the hub 151 of the 100 guide yoke and is provided with downwardly bent ears 176 to keep it firmly seated thereon. The guide yoke is provided with downward extensions 154 having slots 156 cut therein in which the cross-arm 82, above 105

referred to, is guided. Extending outwardly from the lower end of each extension 154 are shoulders 158 which slidably engage the inner surfaces of the walls 22 and 24 of the main frame.

The arrangement of the head piece 140, the pilot carriage 110, guide yoke 150 and the cross-arm 82 and eccentric 90 is such that as the feed screw 100 is rotated the pilot carriage, by reason of the engagement of the nuts 114 with said feed screw, will be moved longitudinally along the main frame, being guided on the rods 120, which during the forward movement co-act with the 15 guide slots 111 formed in the pilot carriage. Due to the engagement of the extensions 116 and 118 of the pilot carriage with the slotted ways 146 and 148 formed in the head-piece 140, the latter element will also 20 be moved in unison with the pilot carriage. It is also clear that the guide yoke and cross-arm 82 being located between the walls 112 of the pilot carriage will also partake of its movement. In addition to its longitudinal movement, the cross-arm is also reciprocated transversely by the eccentric 90 which co-acts with the depending portion 25 83 thereof. As thus constructed it is clear that as the feed screw is rotated the knife blade 80 receives a compound movement, being reciprocated transversely by the eccentric 90 and fed longitudinally by said feed screw. If desired the knife blade can be 30 set in a plane oblique to the axis of the feed screw instead of perpendicular thereto as shown so as to make a diagonal or shearing cut.

The pilot carriage, head piece, guide yoke and cross-arm are arranged with relation to one another so that the plane in which the knife blade operates can be varied to determine the thickness of epidermis to be removed. This adjustment is accomplished by means of turning the adjusting screw 160 so as to raise or lower the guide yoke 150 which slidably carries the cross arm 82 which in turn supports the knife blade.

In order to enable a surgeon, or operator, to set the blade to remove a predetermined thickness of the epidermis, I provide scale markings 141 on the head-piece calibrated to correspond to different thicknesses. The graduations are numbered to correspond with numbers which will be placed on different needle frames 60 each having needles 70 of proper length to be used in stripping different thicknesses of epidermis.

To illustrate, if it is desired to remove a strip of skin, say $\frac{1}{2}$ of an inch thick, the thumb screw will be turned until the arrow 81 on the cross-arm 82 points to graduation number two on the scale 141, and a number two needle frame 60 will be selected having needle points 70 thereon which are slightly less than $\frac{1}{2}$ of an inch in length.

The setting of the knife blade of course is determined by the thickness of the epidermis on the portion of the body from which it is to be removed, and to assist the surgeon in measuring this thickness, I provide a gage 161, Fig. 19, having a plurality of pins 162 secured thereto which are graduated in length and are numbered to correspond with the several needle frames 60. The surgeon selects one of the points 162, which in his judgment is approximately equal in length to the thickness of the epidermis on a portion of the body from which the skin is to be stripped. He then inserts this point and if it shows blood he inserts the next smaller point, if this one does not draw blood he selects a needle frame having points of a length corresponding substantially to the length of the latter pin 162. These pins are numbered to make it a simple matter to choose a needle frame 60 having points of proper length for removing a given thickness of epidermis. This is important because it ensures against the possibility of inserting a needle frame having points 70 of such length that they will be struck by the knife blade 80 as it moved forward. In other words, the numbered needle frames, the calibrations on the head piece and the markings on the gage 161 make the setting 95 practically automatic or fool-proof.

The lead screw 100 is reduced in diameter at one end 104 and fits in a suitable bearing aperture formed in the wall 28 of the main frame, and above the portion 104 is located an oil hole 27 to provide lubrication to this bearing. The opposite end 106 of the lead screw is also reduced in diameter and formed with a slot 108. The reduced end 106 is journalled in a removable bearing 170 which is provided with a shank 172 which is threaded into a tapped hole 25 formed in the end wall 26 of the main frame. A suitable oil hole 29 is formed in the end wall 26 and communicates with a registering hole formed in the shank of the bearing 170 to provide for lubrication of this bearing. A flexible shaft 180 is provided having a head 182 and a tongue 184 which enters the slot 108 to form a driving connection with the lead screw 100. The flexible shaft is covered with a protective casing 185 which is clamped by a knurled head 186 having lugs 187 which engage with similar lugs 177 formed on the fitting 170, the connection being similar in arrangement to the well known bayonet joint.

In operation a needle frame 60 having points of the length desired is inserted into position under the transparent slab 58 of the needle frame holder, this holder is then frictionally secured to the under side of the main frame 20 by engagement of its flanges 54 with the side walls 22 and 24 of the 130

frame. The guard 40 is then or has previously been secured in place by springing its ends into the sockets 32, 34, 35 and 38. The pilot carriage has previously been positioned, as shown in Fig. 1, and the blade 80 adjusted vertically to the desired plane by means of the adjusting screw 160, the accuracy of the setting being accomplished by means of the scale 141 and pointer 81, as 10 will be understood.

The flexible shaft 180 having been previously connected to a suitable source of power, such as a dental motor, not shown, the instrument is given a downward and 15 forward motion to bulge the epidermis and confine it between the front lip 30 of the main frame and the cross-bar 44 and side bars 42 of the guard 40 and to engage the forwardly extending pins 70. It is then given a slight backward movement to engage the oppositely extending pins firmly 20 within the bulged portion of the epidermis. The power is now turned on which causes the feed screw 100 to rapidly rotate, causing 25 the eccentric 90 to reciprocate the knife blade 80 through the cross-arm 82 to which it is connected as above described. It is to be noted that in the starting position the knife blade 80 is located to the rear of the 30 cross-bar 44 of the guard. This permits the motion of the knife to get well under way and overcome inertia of the parts before it starts to cut into the skin. By reason of the engagement of the nut portions 35 114 of the pilot carriage, the feed screw moves said pilot carriage and the associated parts including the guide yoke 150, head piece 140 and cross-arm 82 longitudinally and at the same time the knife blade is being reciprocated transversely. The feed 40 screw moves the guide yoke at a uniform rate and reciprocates the knife synchronously therewith, the compound movement of the knife therefore effecting a continuous 45 uniform cutting action. The pilot carriage is guided in its forward movement by the guide rods 120 and the upper guide grooves 111 formed in the pilot carriage. At the 50 end of its forward movement the pilot carriage comes opposite to the cut away portions 122 of the guide rods 120 which permits the spring 171 to force said pilot carriage upwardly and into contact with the under-surface of the head piece 140 which 55 results in disengaging the pilot nuts 114 from the feed screw 100 so that the said pilot carriage can be quickly returned to its starting position. On the return movement of the pilot carriage its lower grooves 113 ride on the guide rods 120. When the carriage is returned to the starting position its walls 112 come into register with the interrupted portions 124 of the guide rods and exertion of a slight pressure will bring it 60 into position to engage the feed nuts with

the feed screw 100 so that the operation may be repeated.

After a portion of epidermis has been stripped from the body, the instrument can be lifted bodily and the frame holder 50 70 can be slipped out of engagement with the main frame thereby greatly facilitating the handling of the stripped piece of epidermis. The frame holder 50 which carries the needle frame and the strip of epidermis held 75 thereby can be carried by the surgeon to a location near the patient to whom the graft is to be applied. The needle frame is then removed from the frame holder and said needle frame and the graft is applied to the wound of the patient and may be secured by means of bandages, surgeon's tape or the like, it being remembered that the needle frame 60 is formed of flexible material which permits it to readily conform to the shape of 80 that portion of the body to which the graft is made. After the graft begins to knit to the body of the patient the flexible needle frame is removed.

From the foregoing description it will be clear to surgeons, physicians and others engaged in hospital work, that the method herein described marks an advance in this art whereby the epidermis can be quickly 90 stripped from the body with less harm to the person or animal from whom it is removed, than by former methods and that the graft is held taut after removal and hence can be more easily and skillfully applied to the wound of the patient. It is also clear that the utilization of a mechanically or power driven knife is a marked improvement over the primitive hand operated blade formerly used. The parts of the instrument are arranged to permit a clear 100 view of the movements of the knife and the guard holds the portion of skin to be stripped in place. The needle frame holds the skin taut and thereby permits the knife to make a clean cut without dragging the 110 skin along with it, and also prevents the curling of the graft after it is stripped. The transparent bottom of the frame holder provides a flush slab against which the outer surface of the epidermis contacts and 115 allows the surgeon to observe the progress of the cutting operation, it being known to those skilled in the art that the epidermis is sufficiently transparent to permit the knife to show through.

The instrument is so designed that there are comparatively few bolts or nuts used in its assemblage which would tend to gather dust and render the dismantling of the various parts for cleaning rather cumbersome. 125 In dismantling the instrument it is merely necessary to revolve the guide rods 130 a half turn whereby the interrupted portions 132 will be brought into position to permit the removal of the head piece 140. This 130

will permit the removal of the head piece, the pilot carriage guide yoke and cross-arm after the knife blade has been sprung out of engagement and removed from the arms 84 5 of the said cross-arm, therefore, all the parts can be readily cleansed. To further render the instrument antiseptic the metal parts will preferably be either heavily nickelized or else made entirely of non-corrosive materials.

Though I have described with great particularity the steps in the method disclosed and the details of the embodiment of the invention herein shown, it is not to be construed 15 that I am limited thereto, as it is thought that the present invention marks an entirely new advance in the art. Substitution of various known expedients may be made to perform the functions herein described without departing from the invention as defined in the following claims.

What I claim is:

1. The method of performing a skin grafting operation which consists in holding the 25 epidermis taut and stripping it from a body and applying the taut epidermis to the body of the person on whom the graft is to be made.

2. The method of performing a skin grafting operation which consists in applying 30 means to keep the epidermis taut on the body of the person or animal while it is being stripped and stripping the epidermis from the body and applying the taut graft to a 35 wound on a patient.

3. The method of performing a skin grafting operation which consists in first applying a guard and a needle frame to the body 40 of the person or animal from whom the skin is to be stripped to hold said skin taut and above the surrounding skin and stripping the epidermis with a mechanically driven knife and removing said needle frame and the taut 45 graft held thereby and applying it to a wound on a body.

4. A surgical instrument having a blade and means for moving said blade and means 50 on the instrument for guiding the blade below the skin so as to remove from a body a flat piece of skin suitable for a graft.

5. A surgical instrument having a knife blade, means secured to the instrument for holding the epidermis in position to be cut by said blade and means for moving said 55 knife blade to remove from a body a substantially flat strip of epidermis suitable for a graft.

6. A surgical instrument including a blade, 60 means for moving said blade to strip the epidermis, means for holding the epidermis in position to be stripped and means whereby the position of the blade can be adjusted to vary the plane in which it moves to determine the thickness of the strip of epidermis 65 to be removed.

7. A surgical instrument having a reciprocating knife blade, means for holding the epidermis in position to be cut by said blade and means for feeding said knife blade in a direction substantially at right angles to the 70 direction of its reciprocatory movement to strip the epidermis from the body.

8. A surgical instrument having a mechanically driven knife blade for stripping a portion of the epidermis from a body and a detachable needle-frame adapted to assist in holding the epidermis during the cutting movement of said blade and to hold the same taut after it has been stripped from the body.

9. A frame having a plurality of angularly disposed depending needle points adapted to enter the epidermis and hold it taut, so that it can be readily handled in a grafting operation.

10. A frame having a plurality of angularly disposed depending needle points adapted to enter the epidermis and hold it so that it can be readily handled in a grafting operation, said frame being made of flexible material to permit it to yield to conform to the shape of the portion of the body to which the graft is applied, certain of said needle points being inclined in a direction opposite to others to prevent the accidental slipping of the skin relatively to said frame.

11. A frame for holding a graft having a plurality of needles of polygonal cross section secured thereto said needles being arranged in groups, the needles of one group being inclined in one direction and those of another group being inclined in the opposite direction thereto to prevent the graft from slipping away from the frame.

12. A surgical instrument having a mechanically driven blade for stripping a graft 105 of epidermis from a body, guiding and supporting means for said blade and means associated therewith whereby the blade can be adjusted to vary the thickness of the graft removed.

13. A surgical instrument having a mechanically driven blade for stripping the epidermis from a body, guiding and supporting means for said blade and means associated therewith whereby the blade can be 115 adjusted to vary the thickness of epidermis to be removed and means for holding the epidermis in place to be stripped by said blade.

14. A surgical instrument for removing 120 the epidermis having a main frame which is open at the top and bottom, a pilot carriage movable relatively to said frame, a knife blade movable with said pilot carriage, a guide yoke associated with said pilot carriage and arranged to permit a relative vertical movement between it and said pilot carriage, feeding means for moving said pilot carriage longitudinally, and means for automatically disengaging the pilot carriage 125 130

from said feeding means at the end of its forward movement to permit said pilot carriage to be quickly reset to its starting position.

- 5 15. A surgical instrument for removing the epidermis, having a main frame which is open at the top and bottom, a pilot carriage movable relatively to said frame, a knife blade movable with said pilot carriage, 10 a guide yoke associated with said pilot carriage and arranged to permit a relative vertical movement between it and said pilot carriage, feeding means for moving said pilot carriage longitudinally, and means for 15 automatically disengaging the pilot carriage from said feeding means at the end of its forward movement to permit said pilot carriage to be quickly re-set to its starting position, and a frame holder having a transparent 20 parent wall said frame holder being detachably secured to said main frame, a frame slidably mounted in said frame holder having a plurality of needles secured thereto adapted to hold the portion of epidermis 25 stripped by said blade taut on said frame to prevent the graft from curling after it is stripped.

16. In a surgical instrument for stripping a graft of epidermis from a body, a 30 frame holder adapted to be withdrawn from the instrument after the stripping operation, and a needle frame detachably secured to said frame holder and adapted to hold the epidermis taut to facilitate its handling in a 35 grafting operation.

17. In a surgical instrument for stripping epidermis from a body, a frame holder having a transparent bottom wall said frame holder being adapted to be withdrawn from 40 the instrument after the stripping operation, and a flexible needle frame detachably secured to said frame holder and adapted to hold the epidermis taut to facilitate its handling in a grafting operation.

- 45 18. A surgical instrument for removing the epidermis, including a main frame, a pilot carriage movable longitudinally thereof, a head piece slidable on said main frame and having guides which co-act with said 50 pilot carriage, feeding means for moving said pilot carriage longitudinally, a knife blade, means movable longitudinally with said pilot carriage for supporting said knife blade, means for reciprocating said blade 55 transversely and means for releasing said pilot carriage from said feeding means after it reaches the end of its stroke.

19. A surgical instrument for removing the epidermis, including a main frame having side and end walls and open at the top and bottom, a guard secured to said main frame adapted to be pressed against the body of the one from whom the epidermis is to be stripped to cause it to bulge up within the guard, a transversely reciprocating

knife blade movable above said guard, and means for feeding said knife blade longitudinally to strip a portion of the epidermis above said guard.

20. A surgical instrument for removing a 70 graft of epidermis, including a hollow main frame open at top and bottom, a detachable needle frame holder slidably engaging said main frame and having a transparent bottom, and a needle frame detachably secured to said frame holder adapted to hold the epidermis taut before and after it is stripped from the body and a knife blade movable under said needle frame for severing the portion of epidermis held thereby.

21. In a device of the class described, a main frame, a holder slidably secured to said main frame having a transparent bottom, a needle frame slidably secured to said frame holder below the transparent bottom and having a plurality of epidermis engaging needle points secured thereto, a guard below said needle frame adapted to bear against the body from which the epidermis is being stripped and to assist in holding the portion being stripped in contact with said needle frame.

22. In a device of the class described, a main frame, a holder slidably secured to said main frame having a transparent bottom, a needle frame slidably secured to said frame holder below the transparent bottom and having a plurality of epidermis engaging needle points secured thereto, a guard below said needle frame adapted to bear against the body from which the epidermis is being stripped and to assist in holding the portion being stripped in contact with said needle frame and a knife blade movable between said needle frame and said guard for 100 stripping the epidermis from the body.

23. In a device of the class described, a main supporting frame, a frame holder detachably secured thereto and adapted to hold different needle frames each having 110 points of different lengths corresponding respectively to the thickness of epidermis to be removed, a guard mounted below said needle frame holder, a knife movable between said guard and said needle frame 115 holder to strip the epidermis and means for adjusting said knife toward or away from the needle frame holder to control the thickness of the portion of epidermis removed.

24. In a device of the class described, a main supporting frame, a frame holder detachably secured thereto and adapted to hold different needle frames each having 120 points of different lengths corresponding respectively to the thickness of epidermis to be removed, a guard mounted below said needle frame holder, a knife movable between said guard and said needle frame 125 holder to strip the epidermis and means for adjusting said knife toward or away from 130

the needle frame holder to control the thickness of the portion of epidermis removed and a gage for visually indicating the proper setting of the knife blade to remove a predetermined thickness of epidermis.

25. A surgical instrument including a main frame, carriage guides secured thereto, a pilot carriage having two sets of guide ways formed therein, one set being adapted to co-act with said guides during the advance movement of said carriage and the other set being adapted to co-act with said guides during the return movement of said carriage, a pilot nut secured to said carriage, a lead screw adapted to advance said carriage on one set of guides, means for automatically lifting said carriage to disengage the pilot nut from the feed screw at the end of the advance movement of the pilot carriage to permit its quick return, a guide yoke movable with said pilot carriage, means carried by said guide yoke for supporting a knife blade, and means for reciprocating the knife carrying means while the pilot carriage is advancing.

26. A surgical instrument including a supporting frame, two sets of guide rods detachably secured thereto, a pilot carriage guided by one set of guide rods, a head piece guided by the other set of rods and operatively connected with said pilot carriage and arranged to be moved relatively thereto, a guide yoke slidably in said pilot carriage and connected by an adjusting screw with said head piece, a spring carried by said guide yoke and arranged to exert a pressure on said pilot carriage, a cross-arm carried by said guide yoke, a knife blade carried by said cross-arm, a feed screw for moving said pilot carriage and means carried by said feed screw for moving said cross-arm transversely while said pilot carriage moves it longitudinally.

27. A surgical instrument including a supporting frame, a pilot carriage movable longitudinally thereon, a knife blade, means operatively associated with said pilot carriage for supporting said knife blade for transverse movement and means for synchronously feeding said pilot carriage in one direction and moving said knife blade in another direction.

28. A surgical instrument including a supporting frame, a pilot carriage movable

longitudinally thereon, a knife blade, means operatively associated with said pilot carriage for supporting said knife blade for transverse movement and means for synchronously feeding said pilot carriage in one direction and moving said knife blade in another direction, a head piece movable with said pilot carriage and means associated therewith and operatively connected with the knife blade supporting means arranged to adjust the position of the blade relatively to the supporting frame.

29. In a device of the class described a main supporting frame, guide rods detachably secured thereto, members slidably mounted on said guide rods, said rods being formed with interrupted portions to permit the removal of said sliding members for cleansing.

30. In a device of the class described a main supporting frame, a lead screw mounted therein, a pilot carriage operatively engaging said lead screw, a knife blade, means movable with said pilot carriage for supporting said knife blade below said frame and means slidable on said lead screw and movable with said pilot carriage for reciprocating said knife blade.

31. In a device of the class described a main supporting frame, a lead screw mounted therein, a removable bearing to permit the withdrawal of said lead screw for cleansing, and a flexible shaft for driving said lead screw.

32. In a device of the class described, a reciprocating cross-arm having depending portions with undercut tenons formed thereon and a detachable knife blade mortised to fit said tenons, the depending portions of the cross-arm being adapted to be sprung into and out of engagement with said mortises.

33. In a device of the class described, a main supporting frame, a lead screw carried thereby, a pilot carriage co-acting with the lead screw, a knife blade, means movable with said pilot carriage for supporting said blade, means for moving said blade transversely and means for breaking the driving connection between said lead screw and said pilot carriage.

In witness whereof, I have hereunto signed my name.

STANLEY L. APOLANT.
